William Adair

Letters Patent

The schedule referred to in these Letters Patent and making part of the same containing a description in the words of the said William Adair himself of his improvement in the Draft for the cure of Hernia.

Best known that I William Adair of Pleasant Hill Mercer County, State of Kentucky have invented a new and useful improvement in the Draft for the cure of Hernia in the Human body, which is described as following reference being had to the annexed drawing of the same, making part of this specification. The support pad is made of wood of a semi-circular figure as represented at a, covered with buckskin, and secured to the belt or band b, passing around the body by a flat piece of buck skin c, secured to the covering of the block or pad on the flat side d, and then secured to the belt or band before mentioned, which belt or band is made of gunn leather or leather, and when passed around the body is secured by straps d, and buckles e. It is further secured by a strap f, which passes around the thigh, and by another strap g, which passes over the shoulder. The application of this Draft causes a pressure in a direction obliquely upwards and outwards in the direction of the abdominal canal by the elastic hard wooden pad - thus effecting a permanent adhesion in the parts around the external abdominal ring by causing local inflation about the said ring. What I claim as my invention and which I desire to secure by Letters Patent consists in the before described Draft for the cure of Hernia in the Human body.
